WATER-COOLED AMPLIFIER

Armando Marzoli and Fernando Cervellati,
Milan, Italy, assignors to Radio Corporation of
America, a corporation of Delaware

Application June 21, 1941, Serial No. 399,066
In Italy October 29, 1940

6 Claims. (Cl. 315—50)

This invention relates to an amplifier arrangement comprising one or more electron tubes cooled by water circulation and final tuning condenser for radio transmitters.

In radio transmitter equipment, especially power transmitters, the tube or tubes of the end or power amplifier stage are cooled by the aid of circulating water, a cooling jacket being provided for each such tube in which the plate of the tube is mounted in such a way that, with the water being caused to circulate, the outer surface of the plate is brought in contact with the refrigerant. In cases where the amplifier comprises several tubes, the cooling jacket is united preferably in a single unit for each pair of such tubes.

The present invention has as its object an assembly and arrangement of the kind above indicated in which the spaces adapted to contain the plates of each tube consist of chambers in a common tube support and cooling block or header (that is, consisting of a single part) from which extend directly outward fins or ribs forming the fixed plates or stator parts of the condenser which cooperates with the tubes, the whole being preferably combined in a single fused cast piece.

In the appended drawing is illustrated by way of example an embodiment of the arrangement of this invention.

Fig. 1 is a side elevation partly in section.

Fig. 2 is a partial plan view.

In the form of construction as here shown, 1 denotes a head in which, opposite each tube 2 is formed a chamber or space 3, there being disposed in the latter the anode or plate 2' of the tube in such a way that there results a space or gap 4. Tube 2 is fixed in position in chamber 3 by the aid of a collar 5 fitted or formed on the mouth of the chamber and a ring 6 which is screwed upon the collar 5 and engages with the small collar or disk 2" of the tube, with interposition of an elastic washer 7.

In the wall or the shell of chamber 3 is formed a conduit 8 which, by way of the joint 9 as well as pipe 10 and union 15 is connected with the insulating cooling pipe coil 11, while the other end of this coil is united by means of tube 12 with joint 13 attached to the base of chamber 3 opposite its opening 14.

The head 1 is provided with parallel fins 16 which extend transversely thereto. These fins 16 form the stator plates of the power or final-stage tuning condenser of the transmitter.

The rotor of the condenser consists of fins or plates 17 disposed between the fins 16 and supported by the cross shaft 18 which is driven in any convenient manner and is journaled at the ends in ball bearings 20 which are supported, in turn, by small bridge pieces or strips 21 which are united by means of clips 22 to the lateral longitudinal cross pieces 23 of insulation material, the latter, in turn, being attached to the head 1 by means of parts 24.

The assembly comprising the two heads of the type as hereinbefore described mechanically united by means of insulating cross rods 23 and the fins 16 are symmetrical in respect to the axis 10 of the shaft 18 of the condenser and are supported by means of the insulators 19 which insure their being properly electrically insulated because the assembly is subject to the action of high potential applied to the anodes or plates 15 of the tubes 2. For the same electrical reason, the coil 11 is made of insulation material such as porcelain, for instance.

The form of construction as hereinbefore outlined is simple and inexpensive contrasted with the designs heretofore known in the art because the assembly is built up of castings and the space required therefor is reduced for the reason that the stator plates 16 of the condenser are directly attached to the head 1 in which are formed two chambers 3 for the mounting of the tubes 2. The assembly may therefore be mounted at a greater distance from the panels and metallic parts of the radio transmitter, and therefore the residual (stray) capacities are diminished, this being particularly advantageous where short waves are being worked with. For this reason, it is also possible to operate the transmitter at higher frequencies compared with what is feasible with the arrangements known in the prior art.

In the exemplified embodiment here shown, the fins 17 of the rotor comprising parts 17 and shaft 18 of the condenser are constructed in a way so as to co-operate to the same measure and in the same sense with the opposite fixed or stator plates or fins 16 which extend towards the interior of the two end heads of the assembly, they being symmetrical with reference to the shaft 18. However, if desired, the disposition and the shaping of the fixed or stator fins or plates 16 and of the rotor plates 17 could be chosen other than here suggested and shown.

What is claimed is:

55. 1. A variable electric transmitting condenser

comprising a group of parallel spaced rotor plates mounted for rotation on a shaft, two groups of parallel arranged spaced stator plates each having a metallic block portion located at an end of said plates and integral therewith, said block portions having their lengths located at right angles with said stator plates and each having an aperture therein, said shaft located intermediate said stator plates, means for retaining an electron discharge device within each aperture in said blocks, and means for supplying cooling fluid to the aperture in said blocks to cool the electron discharge device.

2. A variable electric transmitting condenser particularly adapted for short wave use, comprising a group of parallel spaced rotor plates mounted for rotation on a shaft, two groups of parallel arranged spaced stator plates each having a metallic block portion located at an end of said plates and integral therewith, said block portions having their lengths located at right angles with said stator plates and each having two apertures therein, said shaft located intermediate said stator plates, means for retaining an electron discharge device within each aperture in said blocks, and means for supplying cooling fluid to the apertures in said blocks to cool the electron discharge device.

3. A variable electric transmitting condenser comprising a group of parallel spaced rotor plates mounted for rotation on a shaft, two groups of parallel arranged spaced stator plates each having a metallic block portion located at an end of said plates and integral therewith, said block portions having their lengths located at right angles with said stator plates and each having an aperture therein, said shaft located intermediate said stator plates, means for retaining an electron discharge device within each aperture in said blocks, means for supplying cooling fluid to the aperture in said blocks to cool the electron discharge device, and insulating bearing means for supporting said shaft and fastened to each one of said blocks.

4. High frequency apparatus including a plurality of fluid cooled electron discharge tubes having at least an anode electrode, a variable condenser having movable plates mounted on a shaft, two metallic cooling blocks, each block

having recessed portions for the anode of each one of said tubes for permitting fluid cooling to circulate around the anode, a plurality of fins forming the fixed plates of said condenser and arranged integral with said metallic blocks, a pair of lateral insulating support members secured to each one of said blocks, the movable plates of said condenser being located in a central position between said blocks and interleaved with said fins, and a bearing means for said shaft located in each one of said lateral insulating supports.

5. High frequency apparatus comprising an amplifier including a plurality of fluid cooled electron discharge tubes having at least an anode electrode, a variable condenser having movable plates mounted on a shaft, a pair of metallic cooling blocks, each block having a pair of recessed portions for the anode of each one of said tubes for permitting fluid cooling to circulate around the anode, a collar around each anode for securing the tubes to said blocks, a plurality of fins forming the fixed plates of said condenser and arranged integral with said metallic blocks, the movable plates of said condenser being located in a central position between said blocks and interleaved with said fins, and bearing means for said shaft insulatingly supported from each block.

6. A radio transmitter comprising an amplifier including a plurality of fluid cooled electron discharge tubes having at least an anode electrode, a variable condenser having movable plates mounted on a shaft, two metallic cooling blocks, each block having recessed portions for the anode of each one of said tubes for permitting fluid cooling to circulate around the anode, a collar around each anode for securing the tubes to said blocks, an elastic washer interposed between said collar and said blocks, a plurality of fins forming the fixed plates of said condenser and arranged integral with said metallic blocks, the movable plates of said condenser being located in a central position between said blocks and interleaved with said fins, and bearing means for said shaft insulatingly supported from each block.
